UNITED STATES PATENT OFFICE.

JAMES KELLY, OF TROY, NEW YORK.

IMPROVEMENT IN MACHINES FOR OILING WOOL.

Specification forming part of Letters Patent No. 47,427, dated April 25, 1865.

To all whom it may concern.

Be it known that I, JAMES KELLY, of Troy, in the county of Rensselaer and State of New York, have invented a new and Improved Machine for Oiling Wool; and I do hereby declare that the following is a full, clear, and exact description thereof, which will enable others skilled in the art to make and use the same, reference being had to the accompanying drawings, forming part of this specification, in which—

Figure 1 is a sectional side elevation of this invention. Fig. 2 is a transverse vertical section of the same, the line x x , Fig. 1, indicating the plane of section.

Similar letters of reference indicate like parts.

This invention consists in oiling the wool between two rollers, one of which runs in a cistern containing the oil, in such a manner that, by the action of the two rollers, the wool is spread in a thin sliver or sheet, and the oil taken up by the lower roller is communicated uniformly to all the fibers.

The cistern is fed from an air-tight can provided with a discharge-pipe which extends from its side close to the bottom, and with an air-tube which extends from its top in such a manner that when the oil in the cistern rises to close the mouths of these tubes no more oil is discharged, but as soon as the oil sinks down below the mouth of the air-tube the oil begins to flow, and thereby a uniform level is kept up in the cistern.

A A' represent two rollers, which have their bearings in standards a , rising from the ends of the cistern B . The lower roller, A', runs in the cistern, and if a quantity of oil or other liquid is poured into said cistern said roller takes up a portion thereof on every revolution. If desired, this roller may be covered with cloth or other absorbent material, which facilitates the operation of taking up the oil, and at the same time prevents injury if some hard substance should be mixed up with the wool to be oiled. The two rollers A A' run close together, and the bearings of the upper roller may be made adjustable, so that said roller bears down upon the lower roller by its

own gravity, or that the two rollers are forced together by means of springs or set-screws. The wool to be oiled is carried to the rollers on an endless apron, and on passing through between the rollers it is pressed out in a thin sheet, and the oil taken up by the lower roll r , A', is communicated uniformly to the fibers of the wool. The cistern B is supplied with oil from a tank or can, C , which is closed air-tight. From the bottom or side of this tank close to its bottom extends a pipe, b , down near to the bottom of the cistern, and through this pipe the oil discharges into the cistern, and another pipe, c , extends from the top of said can down into the cistern to such a depth as may be desired. This pipe forms the air-pipe, and as soon as the oil in the cistern rises to such a height that it closes the mouth of said air-pipe the discharge of the oil stops. By these means an uniform level is kept up in the cistern, and the roller A' is constantly supplied with the requisite quantity of oil, not more and not less. The surplus oil taken up by the roller is scraped off by the doctor D , which is secured to the top of the cistern and made adjustable toward and from the circumference of the lower roller by means of set-screws d , as clearly shown in Fig. 2. By this doctor the oil is spread evenly, and no more oil is allowed to reach the wool than requisite. The surplus oil scraped off by the doctor is returned to the cistern.

This machine is exceedingly simple in its construction, and it performs the operation of oiling wool to the best satisfaction.

I claim as new and desire to secure by Letters Patent—

The two rollers A A', one of which dips in a cistern containing oil, while the other serves to spread the wool, when used in combination with a can, C , and pipes b c , arranged substantially as herein set forth, for the purpose of keeping up an uniform supply of oil to the lower roller.

JAMES KELLY.
